ARTHUR TREVOR DAWSON, OF WESTMINSTER, LONDON, AND JAMES HORNE, OF BARROW-IN-FURNESS, ENGLAND, ASSIGNEES TO VICKERS LIMITED, OF WESTMINSTER, LONDON, ENGLAND.

AMMUNITION-HOISTING APPARATUS.

1,346,302.

Specification of Letters Patent. Patented July 13, 1920.

Application filed June 4, 1915. Serial No. 32,250.

To all whom it may concern:

Be it known that we, Sir ARTHUR TREVOR DAWSON, knight, and JAMES HORNE, both subjects of the King of Great Britain, residing, respectively, at Vickers House, Broadway, Westminster, in the county of London, England, and Naval Construction Works, Barrow-in-Furness, in the county of Lancaster, England, have invented certain new and useful Improvements in or Relating to Ammunition-Hoisting Apparatus, of which the following is a specification.

This invention relates to ammunition hoisting apparatus of the kind in which the projectile and the powder charges are carried in hoist cages from the shell rooms and magazines to the working chamber where they are transferred to an upper or gun loading cage which carries the ammunition to the gun.

According to this invention we employ in addition to the usual projectile hoist cage an auxiliary projectile hoist cage which serves the purpose of carrying projectiles to the working chamber in the event of the usual hoist cage becoming inoperative. The projectile tray of the said auxiliary hoist cage may be pivoted to the latter and may be charged in the shell room when in a horizontal or approximately horizontal position, the tray being moved by hand to a vertical or approximately vertical position prior to the ascent of the auxiliary hoist cage. Means may be provided whereby, as the said auxiliary cage enters the working chamber, the tray is automatically moved to its horizontal or approximately horizontal position for enabling the shell to be removed therefrom in the working chamber.

In order that the said invention may be clearly understood and readily carried into effect, we will describe the same more fully with reference to the accompanying drawings, in which:—

Figure 1 is an elevation showing a constructional form of the invention.

Fig. 2 is an enlarged view of the lower portion of Fig. 1.

Fig. 3 is a part plan of Fig. 2, and

Fig. 4 is a diagrammatic sectional plan of Fig. 1 showing the position of the auxiliary hoist cage in relation to the usual cages.

A lifting rope or cable 1 is attached to

the auxiliary projectile hoist cage A at one 55 of its ends and passes around a pulley 2, which is located above the upper ends of the guide rails B², later described. The other end of this lifting rope or cable is connected to a winding mechanism 3, by 60 means of which the auxiliary projectile hoist cage A is raised and lowered. It is to be noted that the pulley 3 is located above the upper ends of the guide rails B², to such an extent that the cage A will extend above the 65 upper ends of the rails B² to permit the proper pivotal movement of the tray B.

C is the working chamber and C' is the trunk which is connected to the working chamber and moves therewith during the 70 training of the gun turret. This trunk is constructed to receive the usual or main projectile cages C², C³ and the usual or main powder charge cages C³, C³ traveling on guide rails c, and in addition is constructed 75 to also receive the auxiliary projectile cage A which travels to and from the working chamber in a separate compartment C^x forming part of the trunk C. An auxiliary powder charge cage A^x may also be provided 80 as shown in Fig. 4.

A represents the auxiliary projectile hoist cage and A', A' are the guide rails for this cage. B represents the projectile tray of the cage A.

In the example shown the tray B carries on each side thereof a pivot pin b connected to a link B' which is pivoted at b' on the lower part of the cage A. The tray is provided in a position concentric with the pivot pins b, b with rollers b², b² or their equivalent engaging with guide rails B², B². The forward part of the tray carries additional rollers b³, b³ for engaging with the said guide rails B², B² when the tray is swung to 95 its vertical position as shown by chain lines in Fig. 2. In order to enable the said additional rollers b³, b³ to engage with and become disengaged from the guide rails B², B² as required, the latter may be provided with 100 movable sections B³, B³ which can be displaced into a position to permit these rollers to come into alignment with the guide rails or to release the rollers. The said sections are connected to a hand lever B⁴ controlled 105 by a spring b⁴ this hand lever when moved in an anticlockwise direction displacing the sections to the open position shown by chain

- lines in Fig. 2; the tray can then be moved from its vertical to its horizontal or receiving position. The sections are returned to their closed position by the spring b^4 when 5 the hand lever B^4 is released. After a projectile has been placed on the tray and moved rearward until arrested by the rear end of the tray, the latter is rocked to its vertical position, this movement displacing 10 the sections B^3 , B^3 of the rails to the open position in any suitable manner, for example by a cam B^5 on the tray operating upon a part of the aforesaid spring controlled hand lever. When the rollers b^3 , b^3 are in 15 alinement with the rails, the said sections are returned to their closed position by the spring b^4 . It should be observed that when the tray is in its vertical position it can only be moved to its receiving position by means 20 of the said hand lever B^4 . The downward movement of the tray is limited by the co-operation of the cam B^5 with a stop b^5 on the cage.

The rails A' , A' for the cage are straight 25 but the rails B^2 , B^2 are curved at their upper ends so that as the cage enters the working chamber the tray is moved into an approximately horizontal position as shown by chain lines at the upper portion of Fig. 1, 30 the tray being held in this position by means of the aforesaid links B' , B' .

When the tray is in its receiving or horizontal position in the shell-room the cage is prevented from moving by means of spring 35 controlled plungers B^x , B^x (Fig. 3) engaging with holes in the guide rails A' , A' of the cage, these plungers being moved to their disengaged position by means of the lugs b^x , b^x on the tray when it is swung to 40 its vertical position.

What we claim and desire to secure by Letters Patent of the United States is:—

1. In an ammunition hoisting apparatus, an auxiliary projectile cage additional to the 45 usual hoist cage for lifting ammunition to the working chamber, said auxiliary cage being adapted to lift the ammunition while the latter is in a vertical position and to permit its assuming a horizontal position in the 50 working chamber, a trunk which is constructed to receive both the usual hoist cage and the auxiliary projectile cage and in which these cages move during their travel to and from the working chamber, and 55 means for raising and lowering the cage, which means extends to a point above the upper end of the hoist, whereby the ammunition will be free to move from its vertical to its horizontal position.

60 2. In ammunition hoisting apparatus, an auxiliary projectile cage additional to the usual hoist cage for lifting ammunition to the working chamber, said auxiliary cage serving to carry projectiles to the working 65 chamber in the event of said hoist cage be-

coming inoperative, a projectile tray, a link pivoted to the tray and to the auxiliary cage, rollers carried by said tray coaxially with the pivotal connection between the link and the tray, guide rails with which said rollers 70 engage, and means carried by the tray some distance from said pivotal connection for engaging with said guide rails when the tray is raised to its vertical position prior to the ascent of the auxiliary cage. 75

3. In ammunition hoisting apparatus, an auxiliary projectile cage additional to the usual hoist cage for lifting ammunition to the working chamber, said auxiliary cage serving to carry projectiles to the working 80 chamber in the event of said hoist cage becoming inoperative, a projectile tray, a link pivoted to the tray and to the auxiliary cage, rollers carried by said tray coaxially with the pivotal connection between the link and 85 the tray, guide rails with which said rollers engage, and rollers carried by the tray some distance from said pivotal connection for engaging with said guide rails when the tray is raised to its vertical position prior to the 90 ascent of the auxiliary cage.

4. In ammunition hoisting apparatus, an auxiliary projectile cage additional to the usual hoist cage for lifting ammunition to the working chamber, said auxiliary cage 95 serving to carry projectiles to the working chamber in the event of said hoist cage becoming inoperative, a projectile tray, a link pivoted to the tray and to the auxiliary cage, rollers carried by said tray coaxially with 100 the pivotal connection between the link and the tray, guide rails with which said rollers engage, rollers carried by the tray some distance from said pivotal connection for engaging with said guide rails when the tray 105 is raised to its vertical position prior to the ascent of the auxiliary cage, and a movable section of said guide rails for enabling engagement and disengagement of the last mentioned rollers with and from the guide 110 rails to occur.

5. In ammunition hoisting apparatus, an auxiliary projectile cage additional to the usual hoist cage for lifting ammunition to the working chamber, said auxiliary cage 115 serving to carry projectiles to the working chamber in the event of said hoist cage becoming inoperative, a projectile tray pivoted to said auxiliary cage and adapted to be displaced to a vertical position prior to 120 the raising of the auxiliary cage, and means for locking the cage in its lowermost position until the tray is displaced to its vertical position.

6. In ammunition hoisting apparatus, an 125 auxiliary projectile cage additional to the usual hoist cage for lifting ammunition to the working chamber, said auxiliary cage serving to carry projectiles to the working chamber in the event of said hoist cage be- 130

coming inoperative, a guide rail for said auxiliary cage, a projectile tray pivoted to said auxiliary cage and adapted to be displaced to a vertical position prior to the 5 raising of the cage, a plunger carried by the auxiliary cage for engaging with the guide rail when the cage is in its lowermost posi-

tion and means for automatically disengaging said plunger as the tray reaches its vertical position.

In testimony whereof we affix our signatures.

ARTHUR TREVOR DAWSON.
JAMES HORNE.
